UNITED STATES PATENT OFFICE

MELVIN O. JENNINGS, OF LEXINGTON, MASSACHUSETTS, ASSIGNOR TO HARRY H. BECKWITH, OF BROOKLINE, MASSACHUSETTS

SHOE HEATER

Application filed November 12, 1928. Serial No. 674,314.

This invention relates to shoe heaters such as are commonly employed for stiffening box toes comprising thermoplastic material, so that they may be made to conform to the lasts 5 when the shoes are being made. The thermoplastic material of which the stiffeners are made must have a sufficiently high melting point to maintain its stiffness under all conditions to which a shoe is normally exposed. It is therefore necessary to subject the partially formed shoe, in order to soften the box toe sufficiently to form it about the last, to a temperature which is excessive for the leather. For this reason it has been proposed to direct moist vapor into contact with the leather while the stiffener is being heated in order that the leather may not be damaged.

It has been proposed to provide a water supply tank or reservoir for the vaporizer 20 which will feed water automatically as required to the heating unit. In practice, however, trouble has been experienced from the failure of the operator to notice when the supply of water has become exhausted. The 25 parts of the vaporizer are thus liable to become overheated, and when cold water is then supplied breakage or other damage to the hot parts is liable to occur. Where an electrical heating unit is employed in the vaporizer, it is liable to be burned out after the water supply has become exhausted.

An object of this invention, therefore, is to provide mechanism acting automatically when the supply of water in the tank or reservoir 35 is exhausted or nearly exhausted for cutting off the supply of energy to the water heating unit.

Further objects and advantageous details 40 and combinations of parts will appear from a more complete description of an embodiment of this invention shown in the accompanying drawings in which

Figure 1 is a front elevation of the heater.

Figure 2 is a detail section on line 2-2 of Figure 1 showing a shoe in position.

Figure 3 is a detail section on line 3-3 of Figure 1.

Figure 4 is a fragmentary rear elevation of 50 the heater showing the parts in position when

the supply tank has an adequate supply of water.

Figure 5 is a similar view partly broken away showing the position of the parts when the supply of water is exhausted.

Figure 6 is a diagram of the electrical connections.

The heater comprises a base which is adapted to be supported from a bench or table by any suitable means such as standards 2 shown in Figure 1. This base comprises an open topped receptacle 3 along one side, one side wall 4 being laterally extended to form a shelf portion 5. Below this shelf portion and substantially parallel to the outer end thereof is a lower wall 6, this lower wall and shelf defining therebetween a dry heat chamber 7. End walls 8 bridge over the ends of the receptacle 3, the shelf 5 and the lower wall 6 and at their forward ends each is provided with a pair of inwardly directed spaced ribs 9 between which may be engaged a front wall member 20 for a purpose which will later be described. The receptacle 3 is provided with a cover 10, which has a downturned bead 11 along its rear edge which may rest on the upper edge of the rear wall 12 of the receptacle 3. Ends 13 of the cover are arranged to fit within the end walls 8 of the base member, the ends 13 having downwardly extending portions 14 extending into the receptacle 3 to retain the cover member in proper relation to the receptacle. This cover member has its top wall forwardly and upwardly inclined as at 15 to form with the shelf 5 a vapor passage leading from the receptacle 3 forwardly and into which the toe portions of shoes to be treated may be inserted through suitable apertures in the front wall 20.

The construction and arrangement of the casing walls and heating elements herein shown form the subject matter of a divisional application for patent Serial No. 292,732 filed July 14, 1928, for shoe heater.

Within the chamber 7 is positioned a heating unit 40 of any suitable description. Herein shown this comprises an electrical heating unit in the form of a loop which is supported by blocks 41, each carried at the 100

upper end of a stud 42 fixed to the lower wall 6 of the chamber. Nuts 43 are threaded on these studs and the blocks 41 rest thereon, the upper ends of the studs passing into 5 suitable perforations in the blocks. By manipulation of these nuts 43, therefore, the unit 40 may be adjusted vertically toward and from the plate 18. By this means the amount of dry heat to be conducted to the 10 shoe may be adjusted.

Within the receptacle 3 is a second electrical heating unit 50 which is designed to be immersed in water supplied to the receptacle as will later appear.

The receptacle 3 is of comparatively small capacity so that little water is heated at one time and the vapor is produced quickly when desired. For this reason it is necessary to provide a water supply since the water in the 15 receptacle 3 would soon be driven off causing danger of overheating of the unit as well as of failure of moisture to protect the leather portions of the shoe. For this purpose the base member 1 has extending rearwardly 20 therefrom a trough 55 communicating with the receptacle 3 through an opening 56. This trough is designed to receive water from a supply tank which may conveniently be of the barometric feed type comprising a tank 25 60 having a nozzle portion 61 through which it may be filled, the tank being inverted when in use so that the nozzle portion projects into the trough 55 to approximately 30 the desired level of the water in the receptacle 3. This construction provides an automatic feed of the water to the receptacle 3, but it has been found in practice that such tanks as heretofore used may become emptied 35 without the operator being aware of the fact so that there is danger of the supply to the receptacle 3 becoming exhausted whereupon 40 overheating of the unit 50 may occur. Under these conditions if it be attempted to supply cold water to the receptacle 3 damage to the hot parts is likely to result even if the heating unit 50 is not burned out or otherwise 45 damaged by the excessive heat to which it is subjected when it is not immersed in water.

For this reason the present invention provides means by which as the tank becomes emptied to a certain point, the supply of energy to the heating units is automatically cut off. At the same time a visible indication is given of the condition of the water supply 50 so that the operator can not well be unaware of the situation. The tank 60 is arranged to be inverted and held by a support 65 which has an extension 66 pivoted on a pin 67 to the trough. One side of this support, as at 55 68, is upwardly extended and forms a weight which imparts a bias tending to tilt the support about the pivot 67 into the position shown in Figure 5. The tank 60, however, when filled with water and inverted on the 60 support 68 has its center of gravity on the

opposite side of the pivot pin 67 from the weight 68 and is of sufficient weight to maintain the support 65 in horizontal position. As the tank becomes empty, however, the weight 68 overbalances the tank and water, and causes the bias to be effective to tilt the support and tank into the position shown in Figure 5. When this tilting occurs the nozzle portion 61 is raised upwardly from the trough 55, thus permitting the water above 70 the upper end thereof to spill out into the trough thus raising the level of the water somewhat in the receptacle 3. This occurs until the level of the water in the tank lowers to the lower edge of the inside of the nozzle as shown at a in Figure 5. This tilting of the tank furnishes a visual indication to the operator of the fact that the supply of water is exhausted, and according to this invention it is also employed to automatically 75 cut off the supply of energy to the heating units. This is accomplished as follows. The trough 55 has an extension 70 within which is positioned a push button switch having the "off" button shown at 71 and the "on" button shown at 72, this switch controlling the supply of energy to the units 40 and 50. Fixed to the portion 68 of the tilting support is a member 73 so positioned that when the support is in tilted position, it strikes the "off" button, thus opening the switch. The "on" button 72 is engaged by one end of a lever 74 pivoted at 75 to the portion 70, and this lever has a lost motion connection to the 80 tilting support so that when the support is 85 moved to horizontal position the last portion of this motion acts to depress the "on" button 72, thus closing the circuit through the push button switch to the heating units. As shown this lost motion connection comprises 90 a wire 76 pivoted at 77 to the opposite end of the lever 74, the upper end of this wire being formed as a loop 78 in which rides a pin 79 extending between a pair of ears 85 projecting laterally from the member 73. 95 Before the support reaches its horizontal position this pin 79 engages the upper end of the loop 78, pulls upwardly on the lower end of the lever 74 and depresses the push button 72. 100

In Figure 6 is shown the electrical connections to the units, b and c representing the ends of the dry heat unit 40 and d and e representing the ends of the unit 50. These unit ends are connected by bus bars f and g to which energy is supplied from the source h, the push button switch is indicated at k, and there may also be a manually controlled switch m. The switch m being closed the supply of energy to the heating units is therefore dependent on the closing of the switch k which is automatically effected by the position of the tilting support which carries the water supply tank. The manually operable switch may conveniently be placed in 105 110 115 120 125 130

a box 85 at the end of the base member 1 into which the ends of the heating units project and there may also be, if desired, a pilot light 87 therein, to give a visible indication of the condition of the energy supply to the heating units through a window 86.

Since electric heater units are used in the device as illustrated, in order to conform to the underwriters' rules, it is necessary to insulate the device from the ground. As shown this may be accomplished by the use of blocks 90 of insulating material, such as porcelain, and herein shown as cylindrical, each being seated in a socket 91 in the upper face of a frame member 92 carried at the upper ends of the standards 2, the base member 1 having socketed bosses 93, each constructed to engage over the upper end of one of these blocks. In order also that the device may be adjusted to a horizontal position when the supporting bench or table is not level, the upper ends of the standards 2 may slidably fit in sockets 94 extending upwardly into the frame member 92 and be fixed in adjusted position therein by means of set screws 95. Each standard 2 may also have thereon a vertically slidable collar 96 adjustably fixed by a set screw 97 immediately beneath the frame member 92 as a further means of holding this frame member in adjusted position.

The receptacle 3 may be drained of water when desired, for this purpose a drainage opening 98 being shown on Figure 1 which may be closed by a threaded plug or to which a suitable valved connection may be attached.

Having thus described an embodiment of this invention it should be evident to those skilled in the art that various changes and modifications might be made therein without departing from its spirit or scope as defined by the appended claims.

I claim:

1. In a shoe heater, a receptacle, a heating unit in said receptacle, a tank arranged to supply water automatically to said receptacle, an energy supply for said heating unit, and means for automatically cutting off said unit from said energy supply when the water in said tank reaches a predetermined low level.

2. In a shoe heater, a receptacle, an electrical heating unit in said receptacle, a tank arranged to supply water automatically to said receptacle, electrical connections to said unit including a switch, and means acting to open said switch when the water in said tank reaches a predetermined low level.

3. In a shoe heater, a receptacle, a heating unit in said receptacle, a source of energy for said unit, a tank for automatically supplying water to said receptacle, means acting in opposition to the weight of the tank and the water therein to remove the tank from normal receptacle supplying position and of sufficient strength to overcome the weight of

the tank alone, and means for cutting off said unit from said source when said tank removing means acts.

4. In a shoe heater, a receptacle, a heating unit in said receptacle, a source of energy for said unit, a tilttable support normally biased to a tilted position, a water tank carried by said support and arranged to feed water to said receptacle, the weight of said tank and water acting in opposition to the bias of said support and able to overcome said bias only when there is at least a predetermined amount of water in said tank, and means actuated by the movement of said support to tilted position to cut off said unit from said source of energy.

5. In a shoe heater, a receptacle, an electrical heating unit in said receptacle, a switch for controlling the supply of energy to said unit, a water supply tank, a tilttable support for said tank biased to tilted position, the weight of said tank and the water therein acting in opposition to the bias and being sufficient to overcome said bias only when there is a predetermined amount of water in said tank, and means whereby said switch is closed when said support is not tilted and opened when said support is tilted.

6. In a shoe heater, a receptacle, an electrical heating unit in said receptacle, a trough in communication at one end with said receptacle, a support externally pivoted to said trough in position to lie horizontally over said trough, but biased by its weight to tilt at an angle to the horizontal, a water tank constructed to fit in inverted position in said support and having a nozzle extending downwardly into said trough when said support is horizontal, said tank and support being so proportioned that when a predetermined amount of water is in said tank the bias of said support to assume its tilted position is overcome and when less than said predetermined amount of water is in said tank said bias is effective to tilt said support and tank, 110 a push button switch controlling the energy supply to said unit, a member movable with said support and arranged to impinge on the "off" switch button and open the switch when the support assumes its tilted position, a lever 115 having one arm engageable with the "on" button of said switch, and a lost motion connection between said lever and support acting to rock said lever and depress said "on" button to close said switch when said support 120 is moved to horizontal position.

7. In a shoe heater, a receptacle for water, means for heating the water, a barometric water tank for supplying water to said receptacle, and means for automatically moving said tank to an abnormal position when the water therein has been reduced to a predetermined amount.

8. In a shoe heater, a receptacle for water, means for heating the water, a barometric

water tank for supplying water to said receptacle, and a tilting support for said tank normally overbalanced by the contents of said tank, but adapted to tilt when the contents of the tank have been reduced to a predetermined amount.

9. In a shoe heater, a receptacle, a heating unit in said receptacle, a barometric tank for supplying water to said receptacle, and means held against operation by the weight of the tank and the water therein to permit the tank to remain in normal supplying position, and of sufficient strength to overcome the weight of the tank, when the water is substantially exhausted, to move the tank from said normal supplying position.

In testimony whereof I have affixed my signature.

MELVIN O. JENNINGS.
